(57) **CLAIM**

The ornamental design for a stop mechanism for a folding knife, as shown and described.

DESCRIPTION

FIG. 1 is a rear perspective view of a stop mechanism for a folding knife, wherein broken lines show the folding knife in an open position;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a front perspective view of the stop mechanism for a folding knife of FIG. 1, wherein the broken lines show the folding knife in a closed position;

FIG. 9 is a front elevation view of FIG. 8;

FIG. 10 is a rear elevation view of FIG. 8;

FIG. 11 is a left elevation view of FIG. 8;

FIG. 12 is a right elevation view of FIG. 8;

FIG. 13 is a top plan view of FIG. 8; and,

FIG. 14 is a bottom plan view of FIG. 8.

The broken line showing of the folding knife is provided for purposes of environment and forms no part of the claimed design.

1 Claim, 8 Drawing Sheets
